UNITED STATES PATENT OFFICE

150,802

DESIGN FOR AN ANTIRATTLER FOR WINDOW SASHES

Victor S. Meteyer and Francis D. Kamb,
Irondequoit, N. Y.

Application October 2, 1946, Serial No. 133,710

Term of patent 7 years

(Cl. D10—10)

To all whom it may concern:

Be it known that we, Victor S. Meteyer and Francis D. Kamb, citizens of the United States, residing at Irondequoit, in the county of Monroe and State of New York, have invented a new, original, and ornamental Design for an Antirattler for Window Sashes, of which the following is a specification, reference being had to the accompanying drawing, forming part thereof.

Fig. 1 is a front elevation; Fig. 2 is a side elevation; Fig. 3 is a top plan view; and Fig. 4 is a bottom plan view of an antirattler for window sashes, showing our new design.

We claim:

The ornamental design for an antirattler for window sashes, as shown.

VICTOR S. METEYER.
FRANCIS D. KAMB.
